(No Model.)

F. M. PIERCE.

STEAM ACTUATED VALVE.

No. 340,729.

Patented Apr. 27, 1886.

UNITED STATES PATENT OFFICE.

FRANCIS M. PIERCE, OF BROOKLYN, NEW YORK.

STEAM-ACTUATED VALVE.

SPECIFICATION forming part of Letters Patent No. 340,729, dated April 27, 1886.

Application filed January 12, 1886. Serial No. 188,324. (No model.)

To all whom it may concern:

Be it known that I, FRANCIS M. PIERCE, a citizen of the United States, residing at Brooklyn, in the county of Kings, State of New York, have invented certain new and useful 5 Improvements in Steam-Actuated Valves, of which the following is a description.

My invention relates to improved means for operating steam-actuated valves, the details 10 thereof will be hereinafter fully set forth.

In the accompanying drawings, Figure 1 is a longitudinal sectional elevation of the cylinder, steam-chest, and piston of a rock-drilling engine, non-essential details being 15 omitted. Fig. 2 is a sectional plan view through the center of the steam-chest on the lines 2 2 of Fig. 1, part of the flange of the valve being broken away to more clearly show the steam-ports. Fig. 3 is a view similar to 20 Fig. 2, the valve and detachable portions being removed to more clearly show the passages extending therethrough. Fig. 4 is a view of the port-face of the cylinder, a portion thereof being broken away to show the 25 nature and direction of the passages. Fig. 5 is an inverted plan view of the steam-chest. Fig. 6 is a central vertical section on the line 6 6 of Fig. 1. Fig. 7 is a vertical section on the line 7 7 of all the views except Fig. 6.

30 Similar letters denote like parts.

A represents the cylinder of a rock-drilling engine, which may be operated by compressed air, steam, or other fluid.

The invention is applicable to other engines, 35 but is here shown and will be described as applied to steam (or air) rock-drills, it requiring no invention to apply it to other engines to which it is suited.

The cylinder is formed with the usual steam 40 and exhaust ports and passages, lettered, respectively, a, a' .

B is the piston, and b the piston-rod. C is the steam-chest, within which reciprocates a cylindrical valve, D, by means of which the 45 admission to and exhaust from the alternate ends of the cylinder are controlled in the well-known manner. Steam entering at E passes through the valve and steam-passages to the cylinder, the exhaust-steam escaping through 50 the passage a' and exit E'.

The valve D is spool-shaped, and its ends 55 are provided with packing-rings, which fit

the bore of the steam-chest. This valve has a hole through its longitudinal axis, through which passes the bolt F, which is fixed in the 55 steam-chest C, and serves to guide the valve in its reciprocations, and by means of a spline prevents its rolling on its seat. The bolt F is formed with short narrow slots $f f'$, extending inward from each end toward the interior of 60 the steam-chest, and the valve D is formed with small steam-ports $e e'$, leading from its upper side through its longitudinal portion, and adapted to communicate at predetermined periods with the slots in its support F, forming 65 alternating connections between the live-steam supply and the ends of the steam-chest, and by means of which the valve is driven positively back and forth upon its seat in accordance with the movements of the rest of 70 the apparatus.

In the bottom of the steam chest are two cored passages, G H, connecting opposite ends of the steam-chest with the short tubes or passages I K, which lead from the port-face of 75 the cylinder through to its interior. The passages G H pass upward in the walls of the steam-chest and then traverse it in opposite directions, opening upward in the form of narrow ports $g h$ at opposite ends of the steam-chest, so that one end of the steam-chest is at 80 all times in direct connection with the interior exhaust-chamber of the main cylinder.

The piston B is of ordinary construction, and of a length sufficient to cover and close 85 the lower tube, I, when in its extreme upper position, and it is formed with an annular recess, L, at its central portion, which recess should be shorter than the distance between the tubes I K. A pair of openings, $i k$, located in the side of the cylinder A and in the same plane as the tubes I K, respectively, pass through the sides of the cylinder and into the exhaust-passage a' , and whenever the recess L of the piston covers either of the tubes I K it 95 also covers the corresponding exhaust-passage, from which it will be understood that in the ordinary working of the engine one or other of the valve-controlling ports will be closed by the body of the piston, while the other, being 100 covered by the recessed portion thereof, will have free access to the atmosphere.

The operation of the device will be explained with the parts in the positions shown,

the space between the valve and end of the steam-chest being designated by the letter M. Assuming the engine to have made a number of strokes and to be in position to begin the power-stroke, the conditions are as follows: 5 Piston raised; valve lowered; upper steam-passage ready to receive live steam; space M above the valve filled with the steam that forced it down, which is confined therein by 10 the closure of the port e and tube I, resulting from the relative positions of the valve and piston. These conditions prevail until the piston descends far enough for the recess L to establish communication between the tube I 15 and its exhaust, when the steam in the space M is released, and the tube K, representing the opposite end of the steam-chest, closed. The steam, passing through the port e' and 20 passage f', and having no outlet, now accumulates between the end of the steam-chest and the valve and balances that end of the valve, while the unbalanced pressure at the other end drives it to the opposite extremity of the steam-chest. The ports e e' are short, 25 as also are the passages f f', so that before the valve has completed its movement the impelling fluid is cut off, the valve being moved through the remainder of its traverse by the expansion of the now imprisoned force, which 30 holds it in position, notwithstanding the fact that the opposing set of passages are in position to receive live steam, because until the steam confined as just described is liberated the live steam entering the opposite passages 35 is powerless to move the valve, and escapes through its exhaust.

The amount of steam used to throw the valve can be regulated according to the demands of practice by proper adjustment of the 40 size of the ports e e' and the size and length of the slots f f'; and, further, the rapidity and force of its throw can be regulated by the size of the passages G H and tubes I K, the tube I being, as herein shown, reduced in area, so 45 that the exhaust from the upper end of the steam-chest may be somewhat checked, the in-

tention being to practically cushion the valve on its upward throw.

I do not confine myself to the exact details of the construction and arrangement herein 50 shown, as many modifications may be made by those skilled in the art without departing from the spirit of the invention.

Having described my invention, what I claim, and desire to secure by Letters Patent, 55 is—

1. The combination, with the steam-cylinder and steam-chest, of a reciprocating valve controlling the steam and exhaust passages to the cylinder, supplemental steam and exhaust 60 passages for positively actuating the valve, the supplemental steam-passages being controlled by the valve, and means carried by the piston of the engine for alternately opening and closing the valve-controlling passages, as de- 65 scribed.

2. The combination, with the cylinder of a drilling-engine, of a reciprocating spool-shaped valve, a longitudinal fixed support for said valve, steam ports and passages extending from the longitudinal portion of said valve along its support and to the ends of the steam-chest, supplementary exhaust-passages leading from the ends of the steam-chest to the main exhaust, a piston formed with a recess 75 therein and adapted to alternately open and close the valve-operating passages, as described.

3. The combination, with the drilling-engine having a suitable steam-chest, of the 80 spool-shaped valve D, having steam-ports e e', a longitudinal fixed support therefor provided with the steam-passages f f', the exhaust-passages G H, tubes I K, passages i k, and the piston provided with recess L, substantially as 85 shown and described.

In testimony whereof I hereto affix my signature in presence of two witnesses.

FRANCIS M. PIERCE.

Witnesses:

JOHN CUYAT,
WM. L. SAUNDERS.
